CLAIM

We claim the ornamental design for an accessory for calibrator, as shown and described.

DESCRIPTION

FIG. 1 is a front, left and bottom perspective view of an accessory for calibrator showing our new design;

FIG. 2 is a rear, right and top perspective view of;

FIG. 3 is a front, right and bottom perspective view of;

FIG. 4 is a front view thereof;

FIG. 5 is a rear view thereof;

FIG. 6 is a left side view thereof;

FIG. 7 is a right side view thereof;

FIG. 8 is a top plan view thereof; and

FIG. 9 is a bottom plan view thereof; and,

FIG. 10 is an enlarged view of a circled portion A of FIG.

1.

The dash-dash broken lines depict portions of the accessory for calibrator in which the design is embodied that form no part of the claimed design.

The dot-dash broken lines in FIGS. 1 and 10 indicate an enlarged view.
